(57) **CLAIM**

The ornamental design for a basketball hoop assembly, as shown and described.

DESCRIPTION

FIG. 1 is a perspective view of the basketball hoop assembly showing my new design;

FIG. 2 is an enlarged scale, exploded view of the area indicated by circle 2 in FIG. 1;

FIG. 3 is a further enlarged top plan view shown separate from the broken line portions depicted in FIGS. 1 and 2;

FIG. 4 is a bottom plan view thereof;

FIG. 5 is a right side elevational view thereof; and,

FIG. 6 is a left side elevational view thereof.

The broken lines are included for the purposes of illustrating portions of the basketball hoop assembly that form no part of the claimed design. The broken line circle indicating the area of enlargement likewise forms no part of the claimed design. The appearance within the unshaded edge regions of FIGS. 7 and 8 forms no part of the claimed design.
